(57) **CLAIM**

The ornamental design for a cable crimp cover, as shown and described.

DESCRIPTION

FIG. 1 is a top end perspective view of the cable crimp cover of the present design.

FIG. 2 is a bottom end perspective view of the cable crimp cover of FIG. 1.

FIG. 3 is a front elevation view of the cable crimp cover of FIG. 1.

FIG. 4 is a rear elevation view of the cable crimp cover of FIG. 1.

FIG. 5 is a right side elevation view of the cable crimp cover of FIG. 1.

FIG. 6 is a left side elevation view of the cable crimp cover of FIG. 1.

FIG. 7 is a top plan view of the cable crimp cover of FIG. 1.

FIG. 8 is a bottom plan view of the cable crimp cover of FIG. 1; and,

FIG. 9 is a front elevation view of the cable crimp cover of FIG. 1 shown in environmental use.

The broken lines illustrate environmental structure and form no part of the claimed design.

1 Claim, 5 Drawing Sheets
